UNITED STATES PATENT OFFICE.

PETER L. HOFFMAN, OF AURORA, ILLINOIS, ASSIGNOR TO RICHARDS-WILCOX MANUFACTURING COMPANY, OF AURORA, ILLINOIS, A CORPORATION OF ILLINOIS.

TROLLEY-TRACK.

1,116,425.

Specification of Letters Patent.

Patented Nov. 10, 1914.

Application filed March 25, 1914. Serial No. 827,054.

To all whom it may concern:

Be it known that I, PETER L. HOFFMAN, a citizen of the United States, residing at Aurora, in the county of Kane and State of Illinois, have invented certain new and useful Improvements in Trolley-Tracks, of which the following is a specification, reference being had to the accompanying drawings.

10 This invention relates to improvements in trolley-tracks designed more particularly for door-hangers employed in connection with sliding doors located in positions exposed to the weather. With tracks so located, it is customary to provide a guard or shield over the track to protect it and the wheeled carriage that runs thereon and from which the door is suspended.

It is the object of my invention to provide 20 a construction wherein the track rails and the supporting brackets therefor can be made of pieces of sheet-steel over which, and resting upon the brackets and conforming to the shape thereof, is a sheet-metal 25 guard or shield, said track-rails, brackets and guard or shield being all secured together so as to form a single structure capable of being secured in place as a unit. I accomplish this stated object by the construction shown in the drawing and herein-after specifically described.

That which I believe to be new will be set forth in the claims.

In the drawings,—Figure 1 is a perspective view of the track-rails and their attaching brackets,—the guard or shield being removed. The rivets that are used for holding the guard or shield to the brackets and track are shown in section. Fig. 2 is a similar view but showing the guard or shield secured in place.

Referring to the two figures of the drawings, in which corresponding parts are indicated by like reference characters,—5 indicates a rear bracket-member formed of a straight piece of sheet-metal and adapted to rest against a wall or other suitable support. 6 indicates the front member of the bracket, which is also formed from a piece of sheet-metal. This member 6 has a short vertical wall-section 6^a which lies against the rear member 5, an inclined section 6^b, and a vertical wall-section 6^c, which latter stands far

enough removed from the rear bracket-member 5 to receive between them the 55 spaced-apart tracks 7—7. While the bracket-members 5 and 6 are formed separately as shown, yet it is evident that if desired they might be made from a single piece of material. In the construction 60 shown, the two members are secured together by rivets 8. The track proper is formed of the two parallel rails 7—7, each formed, in the construction shown, of an angle-iron, the vertical walls of which rest 65 against the inner faces of the bracket-members and are secured thereto in any appropriate manner,—rivets 9 being used, as shown. 10 indicates a guard or shield made of sheet-metal and extending over the track 70 and brackets so as to effectually cover them. This guard or shield is bent to conform to the bracket-member 6, upon a plurality of which brackets, arranged at intervals, it rests and is secured. It has a short vertical wall-section 10^a, an inclined section 10^b, and a vertical wall-section 10^c that bear against the bracket sections 6^a, 6^b, and 6^c, respectively, and at its upper portion it is bent to form a narrow flange 10^d that will extend 80 over the upper edges of each two bracket-members 5 and 6. 10^e indicates an out-turned extension of the guard or shield below the track, which acts to deflect water away from the door that is suspended below the track. The guard or shield as a 85 whole is secured firmly in place upon the bracket-member 6, the securing means shown being the rivets 8 and 9 before mentioned. In place of such rivets, the parts may be 90 secured together, if desired, by electrical spot-welding. The guard or shield, in addition to serving as a housing to protect the track and the carriage that runs thereon from the weather, serves also to connect the 95 several sustaining brackets, each formed of the members 5 and 6, together, and as such brackets are spaced at a considerable distance from each other, the structure as a whole is light in weight and at the same 100 time very strong. Furthermore, by having the guard or shield 10 connected with the brackets, the complete device can be very quickly and easily secured in place by a heavy screw or bolt passed through the 105 opening 11 that extends through the parts

2
5 and 6^a of each bracket and also through the part 10^a of the guard or shield.

That which I claim as my invention, and desire to secure by Letters Patent, is,—

5 1. As a new article of manufacture, a combined trolley-track and housing comprising, in combination, a plurality of brackets each having a rail-holding member, a track-rail secured to each of said members, a guard or shield corresponding in shape to the shape of one of the bracket members and extending over and secured to such members.

10 2. In a trolley-track, the combination with a track-rail and a securing bracket therefor comprising a vertical attaching section, an inclined section and a second vertical section, of a guard or shield corresponding in shape to the shape of the bracket and rest-

ing thereon, and means for securing said 20 guard or shield to said bracket.

3. In a trolley-track, the combination with a pair of track-rails and a plurality of securing brackets therefor, said brackets being spaced a distance apart and each comprising 25 a rear member and a front member, said front member having a vertical section resting against said rear member, an inclined section and a second vertical section, of a guard or shield corresponding in shape to 30 the shape of the front members of the brackets and resting thereon, and means for securing said guard or shield to said brackets.

PETER L. HOFFMAN.
